UNITED STATES PATENT OFFICE.

JOHN J. TONKIN, OF OSWEGO, NEW YORK ASSIGNOR TO OIL WELL SUPPLY COMPANY, OF PITTSBURGH, PENNSYLVANIA, A CORPORATION OF PENNSYLVANIA.

STEAM-BOILER.

No. 821,552.

Specification of Letters Patent.

Patented May 22, 1906.

Application filed October 5, 1905. Serial No. 281,443.

To all whom it may concern:

Be it known that I, JOHN J. TONKIN, of Oswego, in the county of Oswego, in the State of New York, have invented new and useful Improvements in Steam-Boilers, of which the following, taken in connection with the accompanying drawings, is a full, clear, and exact description.

This invention relates to the class of steam-boilers which are termed "water-tube" boilers, and it has more particular reference to the style of boilers shown in my Letters Patent No. 772,071, dated October 11, 1904.

The object of the present invention is to more effectually separate the water from the steam in generating said steam and to otherwise increase the efficiency of the boiler; and to that end the invention consists of a novel construction and combination of auxiliary devices applied to the boiler, as hereinafter described and as illustrated in the accompanying drawings, in which—

Figure 1 is a vertical longitudinal section of a boiler embodying my improvements. Fig. 2 is a top plan view of the same, and Fig. 3 is a transverse section on the line $z-z$ in Fig. 1.

In the said drawings, A and A' designate two water-legs, which extend across the ends of the boiler and are connected with each other by the longitudinal water-tubes $a-a$, which are inclined from the front water-leg A to the rear water-leg A'.

B denotes the fire-box, which is under the front end portion of the boiler, and C is the fire-flue, which extends from the fire-box to the rear end of the boiler.

The front water-leg A, I prefer to form of a depth to extend across the front of the fire-box to expose said water-leg to the fire, and thus increase the heating-surface of the boiler, while the rear water-leg A' extends only slightly below the lower row of water-tubes $a-a$ and is supported on the end wall D. I preferably interpose rollers $c-c$ between the bottom of the rear water-leg and top of the wall D to allow the tubes $a-a$ to expand and contract longitudinally without straining them.

b represents a baffle-floor composed of fire-brick or tiles placed on the lower row of tubes $a-a$ and extending from the front water-leg A part way toward the rear water-leg A' and leaving thereat an opening d for the passage

of the products of combustion up from the flue C. A similar baffle-floor b' is placed upon one of the intermediate rows of water-tubes and extends from the rear water-leg A' part way toward the front water-leg A and leaving thereat an upward passage d' for the products of combustion, as shown by arrows 60 in Fig. 1.

The crown or top cover L of the boiler is formed of iron or steel bars $e-e$ of inverted-T shape in cross-section and extended across the boiler and mounted at their ends on the side walls E-E, as shown in Fig. 3. The spaces between these bars are closed by means of tiles or bricks e' , supported on the flanges of the bars. The rear end of the said crown is formed of an iron plate f, extending across the boiler and provided with a flanged opening to emit the smoke from the boiler to the smoke-flue, mounted on said plate in any suitable manner not necessary to be shown.

The outer walls of the water-legs are provided with hand-holes closed by removable covers $h-h$ to afford access to the water-tubes $a-a$ for repairing or renewing them.

$h-h$ are tubes extending through the water-legs for inserting or renewing the bricks or tiles of the baffle-floors.

The top of the front water-leg is open and is attached to the bottom of a superposed drum F, which extends horizontally over said water-leg and has in its bottom an opening i , by which it communicates with the water-leg. To the top of the rear water-leg A' at opposite sides of the boiler are attached upwardly-extending pipes j , which communicate with the water-legs and with a horizontal drum F', mounted on said pipes.

$l-l$ are water-circulating pipes, which are disposed longitudinally over the sides of the boiler and extend from the lower part of the front drum F to the pipes j to allow the water to circulate from said drum to the rear water-leg.

The two drums F and F' are disposed in corresponding planes and at a proper elevation above the water-legs to collect the steam generated in the boiler proper. To equalize the pressure of the steam in the two drums, I employ an equalizing-pipe P, which is connected at opposite ends to the upper parts of the drums and communicates therewith. The top of the rear drum F' is provided with

the steam-outlet *o*. To effectually separate the steam from the water of the boiler, I place in the rear drum *F* a dry plate *l*, which I preferably incline from over the end of the pipe 5 *P*, as shown in Fig. 1, and between this dry plate and steam-outlet *o* I place the dry pipe *n*, which conducts the steam to said outlet. The pipes *l* and *P* are provided with expansion-plate joints *l'* to relieve said pipes from 10 strain incident to expansion and contraction thereof.

What I claim as my invention is—

A water-tube boiler consisting of water-legs extending across the ends of the boiler, 15 longitudinal water-tubes disposed inclined from the front water-leg to the rear water-leg and connecting said water-legs, drums

disposed in corresponding planes transversely over the ends of the boiler and communicating with the aforesaid water-legs 20 rearwardly-inclined water-circulating pipes disposed over opposite sides of the boiler and connected to the lower part of the front drum and communicating with the rear water-leg beneath the rear drum, an equalizing-pipe 25 connected at its ends to the upper parts of the aforesaid drums, and a steam-outlet connected to the top of the rear drum as set forth.

JOHN J. TONKIN.
